UNITED STATES PATENT OFFICE.

ANTHONY J. HAMMER, OF ST. LOUIS, MISSOURI, ASSIGNOR TO WILLIAM J. PREISS
AND WILLIAM H. PREISS, BOTH OF ST. LOUIS, MISSOURI.

FUEL ECONOMIZER AND SMOKE CONSUMER.

Application filed January 6, 1928. Serial No. 244,794.

This invention relates generally to fuel economizers and smoke consumers, and particularly to a simple device of the type mentioned which is adapted for convenient attachment to a wall of the combustion chamber of a furnace or similar heat-producing element in such manner that said device will project into said combustion chamber, the predominant object of the invention being to produce means adapted to cause a circulation of air within the combustion chamber of a furnace, whereby combustion of the combustible materials carried with the gases rising from the bed of burning fuel in the furnace may be effected.

Another important object of the invention is to produce a device of this type which is so constructed and arranged that air passing therethrough from the exterior of the furnace will be pre-heated and thus prepared so that it will readily commingle with the combustible gases within the furnace in a manner to effect combustion of said gases. Also, the passing through the device of relatively cool air from the exterior of the furnace has a cooling effect on same and in this manner prevents overheating of the device, whereby the damage which would result from such overheating is avoided.

Figure 1 is a fragmentary vertical section of a standard furnace having my improved fuel economizer and smoke consumer associated therewith;

Figure 2 is an elevation of the device looking toward the inlet end thereof;

Figure 3 is a vertical section on line 3—3 of Fig. 1;

Figure 4 is an elevation of the device looking toward the discharge end thereof.

In the drawing, which illustrates one embodiment merely of my invention, A designates a furnace of standard construction which is provided with a suitable grate B above which is located the combustion chamber C of the furnace wherein combustion of the fuel takes place. The wall of the furnace A is provided with the usual opening arranged to receive a door frame D, and mounted hingedly or in any other suitable manner to said door frame is a standard furnace door E, said door, as is usually the case, being provided with an opening F for the ingress of air, which opening is ordinarily closed by an air-door or damper arranged so that it is capable of manipulation to admit varying quan-

tities of air into the combustion chamber of the furnace. The air-door or damper referred to is not shown in the drawing, inasmuch as its construction, arrangement and operation are well known.

Secured to the furnace door E at the inner face thereof is a rectangular box-like member 1 which is closed at all of its faces with the exception of one, said member 1 being fixed to the door E by means of bolts or other suitable fastening devices 2 which pass through openings in a wall of said member and in the furnace door E (Fig. 1). The member 1 is secured to the door E in such manner that the edges of walls of said member surrounding the open side thereof contact closely with the inner face of the furnace door, whereby air passing through the opening F in the door will enter the interior of the member 1. The wall 1' of the member 1 which is located remote from the inner face of the door E is provided with an opening 3 which is preferably, though not necessarily, of smaller dimensions than the opening F in the furnace door.

5 designates an air chamber which is provided with a pair of oppositely disposed ears 6 at one end thereof, which ears serve to permit of said chamber being secured in place, the end of the chamber 5 at which the ears 6 are located being arranged in contact with the wall 1' of the member 1, and bolts or other fastening devices 7 being extended through apertures in the ears 6 and in said wall 1' to effect the attachment of the chamber 5 to the member 1. The air chamber 5 in cross-section is more or less triangular in shape with the wider portion of the triangle at the top, and said chamber is hollow and is open from end to end thereof. The shape of the opening within the chamber 5 at the opposite ends thereof is approximately the same as the cross-sectional shape of said chamber, but located within said opening intermediate of the opposite ends thereof is a vertically disposed, and preferably integrally formed, wall 8, the presence of which has the effect of dividing the space within the chamber and adjacent to said wall so that openings 9 and 10 are produced at the opposite sides of the wall 8. The lower ends of the openings 9 and 10 are relatively close together and the wall 8 which separates said openings is of such shape that said openings are flared outwardly from each other as they are extended upwardly. Likewise, the width of said open-

ings is greater at their upper ends than at the lower ends thereof. The opening 3 formed in the wall 1' of the box-like member 1 is preferably approximately the same shape 5 as the cross-sectional shape of the opening formed through the chamber 5, and said chamber is secured to the wall 1' in such position that the opening formed through said chamber coincides with the opening 3. Also, 10 the wall of the chamber 5 at the top thereof and at the end which is within the combustion chamber of the furnace is curved downwardly slightly, as indicated at the point designated by the reference character 11 in Fig. 1. The purpose of this arrangement is to provide an overhanging lip which is so shaped 15 that air passing through the chamber 5 will be deflected downwardly thereby, and thus directed toward the bed of burning fuel in the furnace. By referring to Fig. 1 of the drawing, it will be noted that the discharge end of the chamber 5 is curved downwardly and rearwardly toward the furnace door from the outer edge of the overhanging lip. 20 This arrangement permits of air which passes through the chamber 5 dropping down immediately as it leaves the discharge end of said chamber, as indicated by the arrows in Fig. 1. In the use of a furnace provided with my 25 improved fuel economizer and smoke consumer, air passing through the chamber 5 will be pre-heated and will enter the combustion chamber C of the furnace in the manner indicated by the arrows in Fig. 1, the overhanging lip 11 and the fact that the discharge opening of said chamber is curved downwardly and rearwardly from the upper end of the chamber toward the door of the furnace, causing said air to be deflected downwardly toward the bed of burning fuel. The 30 incoming air will drive the gases rising from the burning fuel, which gases include unburned carbonaceous materials as elements thereof, toward the hotter portion of the bed of burning fuel, namely, that portion thereof 35 adjacent to the wall of the furnace remote from the furnace door, and as this incoming air adds the needed oxygen in a heated condition to the gases, combustion of the combustible materials carried with said gases 40 will be readily effected.

It will be apparent, therefore, that in the use of my improved device, combustion of gases within the combustion chamber of a furnace is effected because, first, oxygen in a heated condition and in sufficient quantity to support combustion is added to the gases; and, second, because the gases are driven by the incoming air to a point where they are located immediately above the part of the bed of burning fuel which is ordinarily the hottest portion thereof, where combustion of the combustible materials included as parts of said gases may readily take place.

65 The burning of the combustible materials

carried by the gases as described increases the heating efficiency of the furnace and at the same time reduces the amount of unburned material passing from the combustion chamber through the flue of the furnace, whereby fuel is economized and the amount of smoke is reduced.

In view of the fact that the openings 9 and 10 are flared outwardly with respect to each other as they are extended upwardly 75 from their lower ends, the air passing through said openings is spread over the entire combustion chamber of the furnace, thus supplying oxygen to all of the gases rising from the bed of burning fuel. Also, due to the fact 80 that relatively cool air is passed through the device from the exterior of the furnace, the device is maintained at a temperature below that at which deterioration thereof would take place, whereby losses caused by over-heating of the device are avoided.

I claim:—

1. A device of the class described comprising a chamber of approximately triangular cross-sectional shape and adapted to be connected with a wall of a furnace having an opening formed therethrough to provide communication with air exterior of the furnace, said chamber having an opening formed therein from end to end thereof of approximately the same cross-sectional shape as the chamber, and said opening being adapted for arrangement in coincidence with the opening in said furnace wall, and a vertically disposed wall arranged within the opening 90 formed through said chamber approximately centrally thereof in a transverse direction and extended longitudinally of said opening, said wall being extended from top to bottom of said opening and dividing the portion of 100 the opening within the chamber adjacent to same into a pair of separate openings spaced apart from each other in a horizontal plane, and the last mentioned openings being flared outwardly with respect to each other at their 110 upper portions.

2. A device of the class described comprising a chamber of approximately triangular cross-sectional shape and adapted to be connected with a wall of a furnace having an opening formed therethrough to provide communication with the air exterior of the furnace, said chamber having an opening formed therein from end to end thereof of approximately the same cross-sectional shape 115 as the chamber, and said opening being adapted for arrangement in coincidence with the opening in said furnace wall, a vertically disposed wall arranged within the opening formed through said chamber approximately 120 centrally thereof in a transverse direction and extended longitudinally of said opening, said wall dividing the portion of the opening formed through the chamber adjacent to same into a pair of openings spaced apart 125 130

from each other in a horizontal plane, and the last mentioned openings being flared outwardly with respect to each other at their upper portions, and an overhanging wall portion 5 at the upper portion of the discharge end of said chamber for deflecting air passing therefrom in a downward direction.

3. A device of the class described comprising a chamber of approximately triangular cross-sectional shape and adapted to be connected with a wall of a furnace having an opening formed therethrough to provide communication with the air exterior of the furnace, said chamber having an opening 10 formed therein from end to end thereof of approximately the same cross-sectional shape as the chamber and adapted for arrangement in coincidence with the opening in said furnace wall, a vertically disposed 15 wall arranged within the opening formed 20

through said chamber approximately centrally thereof in a transverse direction and extending longitudinally of said opening, said wall dividing the portion of the opening formed through the chamber adjacent to 25 same into a pair of openings spaced apart from each other in a horizontal plane, and the last mentioned openings being flared outwardly with respect to each other at their upper portions, and an overhanging 30 wall portion at the upper portion of the discharge end of said chamber for deflecting air passing therefrom in a downward direction, said discharge end of said chamber being curved downwardly and rearwardly to permit 35 air passing from the chamber to move downwardly immediately on discharge therefrom.

In testimony whereof, I have hereunto set my hand.

ANTHONY J. HAMMER.
